(57) **CLAIM**

The ornamental design for a beak, as shown and described.

DESCRIPTION

FIG. 1 is a perspective view of a beak showing our new design.

FIG. 2 is a top plan view of the beak of FIG. 1.

FIG. 3 is a rear elevational view of the beak of FIG. 1.

FIG. 4 is a left side elevational view of the beak of FIG. 1, the right side elevational view being a mirror reflection of the left side elevational view.

FIG. 5 is a front elevational view of the beak of FIG. 1; and, FIG. 6 is a bottom plan view of the beak of FIG. 1.
